EDWARD M. LOCKWOOD, OF PHILADELPHIA, PENNSYLVANIA, ASSIGNOR TO C. R. CARVER COMPANY, OF PHILADELPHIA, PENNSYLVANIA, A CORPORATION OF PENNSYLVANIA.

COLLAPSIBLE MANDREL.

1,138,675.

Specification of Letters Patent. Patented May 11, 1915.

Application filed July 17, 1914. Serial No. 851,668.

To all whom it may concern:

Be it known that I, EDWARD M. LOCKWOOD, a citizen of the United States, and resident of Philadelphia, county of Philadelphia, 5 and State of Pennsylvania, have invented an Improvement in Collapsible Mandrels, of which the following is a specification.

This invention relates to rewinding devices for printing or embossing presses or 10 machines of like character and relates more particularly to a collapsible mandrel for winding material.

The invention has for an object to provide a mandrel which operates efficiently as a 15 winding device for paper or like material and which may be readily removed from the roll of wound material in order that it may be again used for winding purposes.

It has for a further object to provide a 20 mandrel simple in construction, comprising few parts and adapted to be easily and quickly adjusted from collapsed condition to operative condition or vice versa.

My invention also comprehends other 25 tails of construction which, together with those above specified will be better understood by reference to the drawings, in which:—

Figure 1 represents a side elevation, partly 30 in section, of a collapsible mandrel embodying my invention; Fig. 2 represents an end elevation of the same; Fig. 3 represents a section on line 3—3 of Fig. 1; Fig. 4 represents a side elevation of the mandrel in col- 35 lapsed condition; Fig. 5 represents a section on line 5—5 of Fig. 4; Fig. 6 represents a detail of one of the fastening studs; Fig. 7 represents a side elevation of a portion of a press showing the mandrel in operative po- 40 sition and in relation to the winding adjuncts; and Fig. 8 represents a side elevation of the mandrel mounted in operative position.

Similar numerals of reference indicate 45 corresponding parts.

1 designates the mandrel arbor consisting, in the present instance, of a polygonal shaped spindle having at one end a reduced cylindrical portion 2 for bearing within a 50 supporting journal, while at the opposite end there is a head 3 fixed to the arbor by means of a key 4. Preferably the head 3 is also polygonal in transverse section and is provided with a counterbored portion 5 adapted to receive the center 6 or end of the

driving shaft as the case may be, while the body of the head seats within a socket member 7 of corresponding shape, which is carried by or forms a part of the re-winding ratchet 8.

9 designates a plurality of bars disposed in parallel relation with respect to the arbor 1 and forming together the body of the mandrel, each being respectively connected by the pivot pins 10, the links 11 and studs 12, 60 with the arbor 1. As here shown there are four of these bars 9 each having connection with the arbor 1 by a pair of the links 11, and it will be noted that the fastening studs 12 are provided with a bearing part 13 be- 65 tween the threaded portion 14 and the head 15 to permit free movement of the links thereon. It will therefore be apparent that the said bars 9 may swing about the fixed pivots formed by the studs 12 and assume 70 either a position in close proximity to the arbor 1 or a position removed therefrom ac- 75 cording to the length of the said links. In order to limit the turning movement of the links 9 in one direction the head 3 is prefer- 80 ably formed of larger diameter than the arbor 1 so that it overlaps the side edges of the links 11 whereby the movement of the said links is limited in the outward direction by the said head. Each pair of the links 11 is 85 pivoted to a different side of the arbor 1 so that the bars 9 are arranged substantially ninety degrees apart and each is therefore arranged to contact with the arbor in col- 90 lapsed condition, though of course this ar- 95 rangement may be varied within the scope of the invention, and I do not wish to be limited thereto, or to the number of bars em- 100 ployed.

In order to maintain the bars 9 in their outermost position to form the body of the winding or rewinding mandrel, I preferably provide a collar 16 mounted for sliding movement upon the arbor 1 and adapted to be maintained in desired position by means 105 of the set screw 17. In the present instance, this collar 16 is provided with a flange 18 of sufficient dimension to overlap or extend beyond the ends of the bars 9 so that when the latter are moved to their operative po- 110 sition the collar 16 may be moved to abut the ends of the bars. In this position it may be fixed by the set screw 17 to hold the parts locked.

In Figs. 7 and 8 I have shown one use of 110

the mandrel where it is employed as a re-winder for the wiping material 19 of a printing or embossing press wherein it is mounted with the end 2 journaled in the bracket 20 while the polygonal head 3 is mounted to turn with the ratchet mechanism 8.

In the operation of the device the wiping material is automatically unwound from the roll 21, passes beneath the wiping mechanism 22 and thence to the mandrel 9 which rewinds it through the operation of a suitable step-by-step mechanism or the like. When the wiping material has been completely wound upon the mandrel the latter is removed from its bearings, the set screw 17 is loosened and the collar 16 may then be slipped along the arbor so that it no longer engages the mandrel bars 9. As soon as this is accomplished the mandrel and all of its parts may be removed from the roll of wound material by grasping the head 3 and drawing the parts outwardly as will be understood. This outward movement of the arbor causes the bars 9 to collapse to the position shown in Fig. 4 since the links being released may turn upon their respective pivots and the device assumes the position shown in Fig. 4. The material may now be discarded and the mandrel again adjusted to its operative position by locking the collar 16 in operative position, after which it is inserted in the machine ready for another winding operation.

It will now be apparent that I have devised a simple and effective type of mandrel wherein the same mandrel may be successively used for rewinding purposes and its removal from a roll of material is accomplished quickly and easily without disassembling any of its parts.

It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details, as the same are susceptible of modification in various particulars without departing from the spirit or scope of the invention.

Having now described my invention, what I claim as new and desire to protect by Letters Patent is:

1. In a device of the character stated, an arbor having a polygonal shaped portion, a pair of links for each side of said portion and pivoted thereto, bars pivoted respectively to each pair of links, a head secured to said arbor at one end and forming an abutment to limit the movement of said bars

in one direction, said head having an apertured portion to receive a centering device 65 and also having a polygonal shape adapted to fit a socket of corresponding shape in a driving member, a collar slidably mounted on the opposite end of said arbor and adapted to engage the adjacent ends of said 70 bars, and means to lock said collar in a predetermined position, whereby in one position said collar maintains said bars properly positioned to form a winding mandrel, and in another position releases said bars to 75 form a collapsed mandrel.

2. In a device of the character stated, an arbor having a body portion of square cross section, combined with bars having a substantially rectangular construction located 80 respectively opposite each face of said square body portion, a pair of links for each bar, each pair of links being pivoted at one end to a face of the body portion of said arbor and pivoted at the opposite end to 85 the face of the aligned bar whereby all of said bars may be moved into contact with the respective sides of the arbor body, each bar seating between its own links and the pair of links of the next adjacent bar, a 90 head secured to said arbor and projecting beyond the side faces thereof to form an abutment in the path of movement of said bars, and a collar slidably mounted on the opposite end of said arbor from said abutment and adapted to hold said bars in contact with said abutment to hold said bars relatively spaced from said arbor to form a winding mandrel.

3. In a device of the character stated, an 100 arbor having a body portion of square cross section, combined with bars located respectively opposite each face of said square body portion, a pair of links for each bar, each pair of links being pivoted at one end to a 105 face of the body portion of said arbor and at the opposite end to the bar whereby the bar is in alinement with an adjacent face, a head secured to said arbor and projecting beyond the side faces thereof to form an 110 abutment in the path of movement of said bars, said head being provided with means for removably securing said arbor to a driving member, a collar slidably mounted on the opposite end of said arbor from said 115 abutment and adapted to hold said bars in contact with said abutment, and means to lock said collar in a position to hold said bars relatively spaced from said arbor to form a winding mandrel.

In testimony of which invention, I hereunto set my hand.

EDWARD M. LOCKWOOD.
